UNITED STATES PATENT OFFICE

JOHN H. BARTLETT, JR., OF OSHKOSH, WISCONSIN, ASSIGNOR TO THE OSHKOSH TRUNK COMPANY, OF OSHKOSH, WISCONSIN, A CORPORATION OF WISCONSIN

GARMENT HANGER

Application filed January 17, 1930. Serial No. 421,366.

This invention relates to travelling cases of the portable wardrobe type and more particularly to a novel form of garment hanger for use therein.

5 These cases are usually box-like in form and comprise a body section and a hinged lid section, the latter being provided within its upper free corners with trolleys, rails, or other fixtures to support the garment hangers 55 by means of which the larger outer garments such as the coats, vests and trousers of a man's wardrobe, and the tailored jackets and skirts, as well as dresses, of a woman's wardrobe are packed in the lid of the case. The smaller 10 garments and toilet articles are packed in the body section of the case and this section is usually partitioned for the purpose. The size of the case as compared with a regulation wardrobe trunk is relatively small, as is 15 necessary in order that the case may be readily and conveniently carried by hand in the manner of the so-called suit-case. The result is that the garments to be packed in the lid section cannot be hung therein in 20 fully extended positions, as in the regulation full-size wardrobe trunk, because the lid is not high enough to accommodate the garments 25 when so extended. To fit within the lid, the garments must be folded transversely on themselves to bring them within the height of the lid which is usually less than 30 one-half the full length of the garments.

One of the objects of my invention is to provide a garment hanger so constructed that 35 the garments may be folded thereon to fit within the lid without undue creasing or wrinkling while retained in the lid.

In accordance with my invention, the garment hanger is of a size to fit within the space 40 afforded by the lid and has a cross-bar at one end over which the portions of the garments on the hanger extending below the bar will automatically fold as the hanger is turned into an inverted position to bring the cross-bar uppermost for engagement with the rails or trolleys in the lid. The length of the hanger is such that the lower ends of the garments thereon, whether coat, trousers, 45 jacket, skirt or dress, will extend below the cross-bar for folding thereover on inverting

the hanger for placing in the lid. The hanger has a shoulder portion at the other end to fit within and support the shoulder portion of the coat or jacket, as the case may be. To accommodate a pair of trousers or a skirt, the 55 shoulder portion of the hanger has a pair of slots therein, which when the trousers or skirt is transversely folded on itself may have its folded sections inserted through the slots from one side of the hanger for engagement 60 with the bar-like portion of the hanger between the slots. The hanger has a mid-section which rigidly joins the cross-bar to the shoulder portion and this mid-portion or joining section is disposed centrally with respect to the other sections and is relatively 65 narrow so that all of the depending portions of the garment on the hanger may be on the same side thereof for automatic folding over the cross-bar on inverting the hanger for 70 packing in the lid. The hanger when taken from the lid is turned to bring the cross-bar lowermost and in so doing the garments automatically unfold and may be removed from the hanger or left thereon for hanging up in 75 a closet, the hanger having a hole or tab at its upper end for the purpose.

The invention consists further in the matters hereinafter described and claimed.

In the accompanying drawings:

Fig. 1 shows a hanger of my invention with garments thereon packed in the lid of a portable wardrobe case;

Fig. 2 illustrates a coat and a pair of trousers arranged on the hanger before the 85 latter is inverted for placing in the lid of the case; and

Fig. 3 is an enlarged vertical sectional view taken through the assembly of Fig. 2 on line 3-3 thereof.

In the drawings, 1 indicates the body of the case, and 2 indicates the lid-section which is hinged to the body at its rear wall, as in cases of this character. When the lid is closed, it is locked to the front wall of the 95 body through the medium of any suitable form of locking devices, which, as shown in Fig. 1 comprise a pair of hasps 3, 3 on the lid and slotted keepers 4, 4 therefor on the body. The keepers have locking cylinders 100

5, 5 by which the bolts in the keepers may be withdrawn from the hasps to unlock the lid. Located within the lid 2 within the upper free corners thereof are the rails or trolleys 6, 6 for the hangers, said fixtures being supported in the lid by suitable brackets 7, 7 as shown.

The garment hanger of my invention is designed to fit within the space afforded by 10 the lid 2, and comprises a cross-bar 8 at one end and a shoulder portion 9 at the other end, said shoulder portion being made sloping to fit within the shoulder of a coat, jacket, and the like. The bar 8 and shoulder portion 15 9 are rigidly connected by a joining section 10 which is centrally disposed between said parts, as shown. All parts of the hanger are in the same plane, and they are preferably integral, being made from a single 20 piece or layer of wood or sheet material, or in a laminated form as from thin plies of the desired material. A man's coat 11 is shown on the hanger in the drawings. The coat is placed on the hanger in the manner shown in 25 Fig. 2 with the shoulder portion of the coat hung over the shoulder portion 9 of the hanger, and with the depending portions of the coat, including the sleeves, all on the same side of the cross-bar 8. This is rendered possible because the joining section 10 is relatively narrow in width and is disposed centrally with respect to the portions 8 and 30 9 which it rigidly connects.

The length of the hanger, that is, the distance between the cross-bar 8 and the shoulder portion 9 along the joining section 10, is considerably less than the full length of the extended garment 11 on the hanger and as a result the lower ends of the garment extend below the cross-bar 8, and being on the 40 same side of the cross-bar will automatically fold over the latter on inverting the hanger to bring the cross-bar 8 uppermost as shown in Fig. 1. The ends of the cross-bar 8 extend beyond the shoulder portion 9 and are there provided with notches or recesses 12, 12, which open towards the shoulder portion 9 and are thus on the under side of the cross-bar 8 when inverted to engage over the upper 45 portions of the rails or trolleys 6 when the hanger is placed in the lid. The ends of the cross-bar 8 at the notches 12 may be made hook-shaped and extend sufficiently above the upper edge of the cross-bar to provide 50 a recess extending along the bar between the hooks to accommodate the loop in the garment portions which are folded over the bar.

The shoulder portion 9 of the hanger is 55 provided with a pair of substantially parallel slots 13, 14 extending cross-wise of the hanger, as shown in Figs. 1 and 2. These slots permit another garment, such as a pair of trousers 15 or a woman's skirt to be placed on the hanger when such garment is folded

transversely and inserted through the slots with the fold engaging over the portion 16 of the hanger between the slots, as shown in Fig. 2. The folded sections of this garment are inserted through the slots in a manner that the sections will lie on the same side of the cross-bar 8 as the depending portions of the other garment 11. The ends of the folded sections of the garment extending through the slots extend below the cross-bar 8 and will automatically fold over the cross-bar with the terminal portions of the other garment as the hanger is inverted to be placed in the lid 2 of the case.

In practice, the skirt or trousers are first 80 applied to the hanger and then the jacket or coat is applied so that the skirt or trousers are located inside of the jacket or coat and both garments are suspended from the hanger with their depending portions all on the same 85 side of the cross-bar 8 and extending below same prior to inverting the hanger for placing in the lid of the case.

With a hanger in the form shown and described, the depending portions of the garments on the hanger will only require one folding over cross-bar 8 on inverting the hanger to bring the garments within the space afforded by the lid. Thus undue creasing and wrinkling of the garments is avoided 90 as the folding is reduced to the minimum. The hanger is simple in construction and all of its parts being rigidly connected and in the same plane makes handling of the hanger 95 easy and convenient both when placing the hanger in and removing it from the case and when turning the hanger either to fold the garments over the cross-bar 8 or unfolding them to remove the garments from the 100 hanger.

The hanger at its shoulder portion 9 is provided with a centrally disposed outwardly extending part 17 about which the collar of the coat or jacket fits to prevent the garment from sliding off the hanger. The part 17 may be provided with a hole 18 for a loop 19 whereby the hanger may be suspended 110 from a hook in a closet with garments thereon in extended position when the hanger is removed from the lid of the case. With the depending or terminal portions of the garments folded on the cross-bar 8 when inverted the garments are supported by said bar and cannot fall down to be in a heap in 115 the case.

The details of construction shown and described may be variously changed and modified without departing from the spirit and scope of my invention.

I claim as my invention:

1. A garment hanger having all portions in the same plane and comprising, a cross-bar at one end, a shoulder portion at the other end, and a mid-section rigidly connecting the cross-bar to the shoulder por-

tion, said mid-section being relatively narrow, so that a garment hung on the shoulder portion may have its depending portions all on the same side of the cross-bar, said shoulder portion having a pair of substantially parallel slots therein extending cross-wise of the hanger to permit another garment when folded transversely on itself to engage the shoulder portion between the slots and lie on the same side of the cross-bar as the depending portions of the first garment, said hanger having a length less than the full length of the depending portions of the garments thereon, so that the latter will automatically fold over the cross-bar when inverting the hanger to bring the cross-bar uppermost.

2. A garment hanger having all portions in the same plane and comprising, a cross-bar 20 at one end, a shoulder portion at the other end, and a mid-section rigidly connecting the cross-bar to the shoulder portion, said mid-section being relatively narrow, so that a garment hung on the shoulder portion 25 may have its depending portions all on the same side of the cross-bar, said shoulder portion having a pair of substantially parallel slots therein extending cross-wise of the hanger to permit another garment when 30 folded transversely on itself to engage the shoulder portion between the slots and lie on the same side of the cross-bar as the depending portions of the first garment, said hanger having a length less than the full 35 length of the depending portions of the garments thereon, so that the latter will automatically fold over the cross-bar when inverting the hanger to bring the cross-bar uppermost, said cross-bar extending beyond 40 the ends of the shoulder portion and having notches therein opening toward the latter.

3. A garment hanger having all portions in the same plane and comprising, a cross-bar at one end, a shoulder portion at the 45 other end, and a mid-section rigidly connecting the cross-bar to the shoulder portion, said mid-section being relatively narrow, so that a garment hung on the shoulder portion may have its depending portions all on the 50 same side of the cross-bar, said shoulder portion having a pair of substantially parallel slots therein extending cross-wise of the hanger to permit another garment when 55 folded transversely on itself to engage the shoulder portion between the slots and lie on the same side of the cross-bar as the depending portions of the first garment, said hanger having a length less than the full 60 length of the depending portions of the garments thereon so that the latter will automatically fold over the cross-bar when inverting the hanger to bring the cross-bar uppermost, said hanger having means at its 65 shoulder portion whereby the hanger may

be suspended while the cross-bar is lowermost.

4. A garment hanger having all portions in the same plane and comprising, a cross-bar at one end, a shoulder portion at the other end, and a mid-section rigidly connecting the cross-bar to the shoulder portion, said shoulder portion having a pair of substantially parallel slots therein extending cross-wise of the hanger to permit a garment when folded transversely on itself to engage the shoulder portion between the slots and lie on one side of the cross-bar, said hanger having a length less than the folded portions of the garment so that the latter will automatically fold over the cross-bar on inverting the hanger to bring the cross-bar uppermost.

In testimony whereof I affix my signature.
